3 Claims. (Cl. 204—250)

It is, accordingly, a principal object of the invention to provide for improvements in the mounting of anodes in electrolytic cells.

Another object is to provide such improvements while, 5 at the same time, simplifying the structure employed therefor.

A further object is to provide more positive and effective mounting of the anodes for electrolytic cells than has heretofore been thought possible.

10 A still further object is to facilitate accurate adjustment of anode plates beyond anything that has heretofore been achieved.

Further and more detailed objects are to facilitate the 15 exact positioning of anodes in the assembly of an electrolytic cell, to provide for more positive conductance of electricity to the anodes, and to provide for such conductance being effected in a more uniform manner.

Further and more detailed objects of the invention will 20 in part be obvious and in part be pointed out, as the description of the invention taken in conjunction with the accompanying drawing proceeds.

In the single figure of that drawing, a portion of an 25 electrolytic cell embodying the invention is shown partly in section and partly in elevation.

Referring to the illustrative embodiment of the invention in detail, the electrolytic cell shown has a cover 1 provided with an opening 2 therethrough for the passage of the supporting stem 3 of an anode plate 9. The stem 3 is preferably formed of graphite like the anode plate itself. An upstanding collar 4 is secured to the upper surface of the cell cover 1, surrounding the opening 2. The rubber cover 5 applied to the inner surface of the cell cover 1 has a sleeve portion 5' which extends up through the opening 2 and is turned over the collar 4 and down the outside thereof. A vertically extensible gland or tube 6 of rubber, or other suitable material, has its lower end overlying the downturned portion of the sleeve 5'. That lower end and the downturned portion of the sleeve 5' are clamped together in tight engagement and such downturned portion is clamped against the outer surface of the collar 4 by means of a split clamping ring 7, having suitable take-up means at the opposed ends thereof.

The upper end of the gland 6 lies against the outer 45 surface of a collar 11 of hard, insulating material inset into the upper outer corner of the stem 3. This upper end of the gland 6 is secured in leak tight engagement with the outer surface of that collar by means of a split clamping ring 10 similar to the ring 7. In this way the gland member 6 is protected from the effect of the heat 50 carried by the graphite anode stem 3 when the cell is in operation.

At its lower end the graphite stem 3 is suitably secured in the anode plate 9, threading being the means here 55 illustrated at 3' for effecting that securing. The mounting of the stem 3 from above is effected by first carrying the stem 3 by means of a carrier and conductor bar 8. The bar 8, formed of brass or other suitable conducting material, harder than the graphite stem 3, has its lower 60 portion threadedly secured at 8' within a threaded bore provided down into the stem 3.

The upper part of the bar 8 passes through an opening 65 in the bridge member 13 which is fixedly mounted above the cover 1 by suitable mounting and conducting supports 13'. These supports may be of such size, position and number as required for effective support and for conducting the electricity as desired. The bridge member 13 extends along above the cell cover 1 carrying the various anodes of the cell as it is itself carried by the cell cover.

70 The bar 8 is effectively adjustably clamped in place by a clamping arrangement which also conducts elec-

This invention relates to electrolytic cells, particularly chlorine alkaline cells, and is particularly concerned with improvements in the mounting of the anodes for such cells and in the conducting of electricity to the anodes.

Heretofore the conducting of electricity to anodes in electrolytic cells has been carried out in a variety of manners. Various kinds of conducting bars, or rods, have been used extending longitudinally of the cells, with the common arrangement being for the rods, or bars, to be carried over the cover of the cell by carrier bars, while the rods or bars in turn have carried the anodes at spaced positions therealong. Such conducting bars, or rods, have been connected to the anodes by separate conductors engaging the conducting and supporting shafts of the anodes. As electrolysis proceeds in such cells, it results in the disintegration or wear of the anodes, which takes place chiefly on their undersurfaces. This makes necessary periodic adjustment of the position of the anodes to avoid, among other things, uneven distribution of the electric current among the various anodes.

To provide for such adjustment the conductors from 35 the conducting bars or rods to the anode shafts must be flexibly formed. They can be either in the form of multi-conductor cables, or of copper strips rectangular in cross-section and sufficiently thin to provide flexibility. Here the current carrying capacity of such strips would be 40 achieved by imparting sufficient width to them.

The disadvantages of the prior art constructions just described are that they are complicated, and adjustment of the position of the anodes is difficult. This latter is particularly true in the course of initial assembly of the cells and of reassembling the cells after they have been 45 disassembled.

The foregoing and other disadvantages of the prior art constructions are avoided by the structure of the invention which, in addition, goes several steps further in advancing the art. Generally speaking, this is achieved by employing the cover of the cell as the principal conductor for the electricity, and mounting a carrier bridge for the anode shafts on and above the cell cover. This bridge supports the anodes and is supported itself in spaced relation with respect to the cell cover with the supporting arrangement serving to conduct the electricity to the anodes. In this manner the steps that have to be taken for effective adjustment of the anodes are materially reduced, for the only adjustment necessary is that of the anode supports, or shafts, with respect to the bridge.

Insofar as the conducting of electric current to the anodes is concerned, the bridge and supporting structure therefor which carries the anodes and is itself carried by the cell cover, can be readily dimensioned to conduct the electricity with a minimum loss of energy. Also, exactly even distribution of electric energy to the shafts of the respective anodes is assured. Finally, effective adjustable mounting of the anodes with respect to the bridge, as well as provision for the removal of the anodes, can be readily achieved, since the prior art limitations on such adjustment and removal are eliminated.

tricity to it from the bridge member 13. This arrangement involves an annulus 12 integrally secured to the upper surface of the bridge 13 surrounding the opening therein through which the bar 8 passes. The annulus 12 is horizontally bored at a plurality of positions, preferably three in number and evenly spaced, for the passage of clamping screws 14, the inner ends 16 of which are preferably conically formed for effective seating in conical recesses provided therefor in the outer surface of clamping segments 15. These clamping segments, the same in number as the screws 14, have their inner surfaces formed for mating engagement with the exterior surface of the bar 8.

It will be apparent from the provision of the three point suspension of the bar 8 that exact horizontal positioning of the same can be effected by the adjustment of the screws 14. Furthermore, of course, vertical positioning of the bar 8 and thus of the stem 3, which together make up the anode shaft, and the anode plate 9 can be readily and surely effected by the proper tightening of the clamping screws 14. Not only does this make for a tight effective physical mounting capable of being readily adjusted, but also it provides an effective path for the flow of electric current from the bridge 13 through the annulus 12, the screws 14 and the segments 15 to the conducting and supporting bar 8.

Suitable means is provided for engaging the bar 8 to hold it and move it vertically as desired. In this instance, such means takes the form of the projection 17 extending from the upper end of the bar 8, which projection is perforated at 17' for the reception of any suitable holding or hoist means.

The provision of a composite supporting shaft for the anode plate involving a graphite stem and a conductor and supporting bar of harder material received within that stem, eliminates a number of the drawbacks of prior art constructions and involves substantial improvement over the prior art. In the prior art, where anode plates were carried by supporting shafts of material subject to the corrosive action within the cell, the attempt was made to protect against such action by applying a sheathing or covering to shafts of non-corrosive materials, which by their natures were generally non-conductors of electricity. This practice had various drawbacks. For one thing it was difficult to make a tight seal where the covered shaft engaged the anode plate. Above that, the covered shaft traversed the part of the cell containing such corrosive materials as wet chlorine gas when the cell was in operation, defects in the coverings caused trouble.

For one thing, should the coverings have flaws in them, they might crack or become porous, allowing the corrosive material to attack the conducting stem without the results of it being detachable from outside of the cell until something serious happened. The possibility of the covering cracking was always present, since normally the coefficients of heat expansion for the conducting member and the coating member would be quite different, while the heat gained in the operation of these cells is quite substantial. At their best, the coatings were rather in the nature of necessary nuisances, for they were fairly thick, would normally be non conductors, and so they would just take up space in the cell.

It is apparent from the foregoing description of the invention that these specific drawbacks of the prior art constructions, as well as the general ones initially pointed out, are eliminated by the invention construction. The graphite supporting stem 3, being a good conductor of electricity and being, at the same time, highly resistant to the corrosive action of the contents of the cell, is the best means for supporting the anode plates which are themselves made of the same material. No problem of difference in materials is involved where the stem and the plate are joined together. Fully effective electrical

conductivity between the bar 8 and the stem 3 is achieved by proper forming of the threads 8. Nowhere is the bar 8 exposed to the action of the cell contents. In addition, the construction of the invention facilitates precise and effective adjustment of the position of the anode plate 9 by the effectiveness of the clamping action which can be exerted by the segments 15 against the supporting bar 8, of brass or other hard material. Precise adjustment here can be achieved through the proper threading of the adjusting screws 14 and the bores in the annulus 12 receiving them. Even and effective conducting of electricity from the bridge structure to the anode shafts is also provided for. Leakage of gas from the cell is doubly protected against by the sleeve 5' and the gland 6 while, at the same time, permitting the desired adjustment of the stem 8.

Though in the foregoing, specific materials and specific assemblies of elements have been shown and described, it is to be understood that such showing and description are for the purpose of illustrating the invention and that the invention is not to be construed as being limited thereby. Speaking more generally, it will be clear to those skilled in this art that the practice of the invention lends itself readily to various modifications.

Having described my invention, what I claim as new and desire to secure by Letters Patent is:

1. In electrolytic cell construction, a cell cover formed as the principal conductor of electricity for the anodes of the cell, a one-piece elongated strip of conducting material forming a supporting and conducting bridge positioned above said cover and extending longitudinally along the length thereof in spaced relation with respect thereto, vertical supporting members rigidly and fixedly secured at their lower ends to said cell cover and at their upper ends to said bridge member, at spaced positions along the length of said cell, said cell cover and said bridge being formed with a plurality of pairs of aligned openings therethrough, a plurality of anode plates within said cell, an anode stem extending upwardly from each of said plates, one of said stems extending through each of said pairs of openings, said stems extending to a position above said bridge, said supporting members for said bridge being positioned at either side of said stems, mounting and conducting means carried on the upper surface of said bridge and surrounding said stems, said means including elements for clamping said stems in desired vertical position and for conducting current from said bridge to said stems, said clamping means including adjustable means for enabling said stems to be adjusted vertically, said bridge and said clamping and adjustable means being the sole means providing vertical support for said stems and for conducting electricity from said cell cover to said stems.

2. Electrolytic cell construction as in claim 1 said adjustable means including a plurality of current conducting shoes in clamping engagement with said anode stems.

3. Electrolytic cell construction as in claim 1, said mounting and conducting means including rings surrounding said anode stems, said rings being integrally secured to the upper surface of said bridge, segments within said rings formed to engage said stem and adjustable members carried by said rings and engaging said segments for clamping the same against said stem.
